[57] CLAIM

The ornamental design for a combined freezable water bottle and tray, as shown.

DESCRIPTION

FIG. 1 is a perspective view of the combined freezable water bottle and tray showing my new design;
 FIG. 2 is a top plan view thereof;
 FIG. 3 is a front elevational view thereof;
 FIG. 4 is a side elevational view thereof taken along the line 4—4 of FIG. 2;
 FIG. 5 is a side elevational view thereof taken along the line 5—5 of FIG. 2;
 FIG. 6 is a side elevational view thereof taken along the line 6—6 of FIG. 2;
 FIG. 7 is a side elevational view thereof taken along the line 7—7 of FIG. 2;
 FIG. 8 is a bottom plan view thereof; and
 FIG. 9 is a sectional view thereof taken along the line 9—9 of FIG. 4.
